UNITED STATES PATENT OFFICE.

AUGUST E. STEINHAUSER, OF PHILADELPHIA, PENNSYLVANIA.

BOTTLE-CAP REMOVER.

1,293,969.

Specification of Letters Patent.

Patented Feb. 11, 1919.

Application filed March 12, 1918. Serial No. 221,953.

To all whom it may concern:

Be it known that I, AUGUST E. STEINHAUSER, a subject of the Emperor of Germany, residing at Philadelphia, in the county of Philadelphia and State of Pennsylvania, have invented new and useful Improvements in Bottle-Cap Removers, of which the following is a specification.

This invention relates to improvements in 10 bottle caps of the type commonly made of sheet metal and employed for sealing bottles of various kinds, and particularly to metal bottle caps of that character having crimped portions or interlocking projections to engage under shoulders or within locking recesses on the bottle mouth, whereby the cap is normally held in position against displacement.

The primary object of the present invention 20 is to provide novel, simple and inexpensive means, forming a permanent part or fixture of the cap, for removing the same from the bottle without the necessity of employing an auxiliary removing device or opener.

A further object of the invention is to provide a bottle cap opener which will normally lie in close proximity to the cap and bottle, in an out of the way position, and 30 which may be adjusted for use to exert a powerful leverage, when desired, for removing the cap in an easy, convenient and expeditious manner.

The invention consists of the features of 35 construction, combination and arrangement of parts hereinafter fully described and claimed, reference being had to the accompanying drawing, in which:

Figure 1 is a side elevation of the neck of 40 a bottle, showing a closure cap embodying my invention applied thereto;

Fig. 2 is a top plan view of the bottle, with the cap and opener applied thereto;

Fig. 3 is a view in elevation, taken at an 45 angle to that shown in Fig. 1, showing the opening lever turned to an operative position for use.

Referring to the drawing, 1 designates the neck portion of a bottle or similar container, to which is applied a metallic closure cap 2 of a type in common use. This cap surrounds the rim portion of the neck 1, and is provided with crimps, corrugations or instruck projections 3 to engage under 55 a shoulder or into depressions formed in the bottle neck for the purpose of holding

the cap in sealing position. The cap may be provided, as usual, upon the interior thereof, with any suitable type of sealing means to prevent leakage, such as the usual disks 4 and 5 of cork and paraffined or oil paper, respectively. The cap shown is also of a type having an upstanding annular bead or rim 6 extending above the level of its crown portion and connecting the same with the depending flange forming the body of the cap.

In accordance with my invention, the flange or body 7 of the cap is provided at one side with a depending tongue or projection 8 integral with the lower edge of the flange 7 and stamped or otherwise formed therewith. To this lug is suitably secured an opening lever 9, in the form of a ring of sufficiently greater diameter than 75 the neck 1 to surround the same and to be swung in a vertical plane from a horizontal to a vertical position, as indicated in dotted lines in Fig. 1. The ring 9 may be made 80 of wire or other suitable material and may be pivoted or soldered at one point to the tongue 8, which may be wrapped around the ring one or more times, to obtain greater security of connection.

Normally, the ring or lever 9 lies in a 85 horizontal position parallel with the lower edge of the cap and just below the same, and is adapted to be placed with the cap in such position upon the bottle neck when the cap is applied. The diameter of the 90 ring but slightly exceeds the diameter of the neck 1, this excess in diameter being just sufficient to enable it to be swung upwardly to a vertical position and to clear the cap in such movement. When disposed in the normal position stated, it will be 95 evident that the ring will lie in close proximity to the bottle and cap and will thus offer no obstruction to the storage of the bottle with others in a case or cabinet, or 100 present any surfaces liable to injure the hands or clothes of a person handling the bottle. When, however, the ring or lever 9 is turned to a vertical position, it forms a handle whereby the tongue 8 will be 105 straightened out to loosen the flange of the cap and permit the cap to be readily and conveniently withdrawn from the bottle neck. Where the ring or lever is fixed to the tongue 8, the rim 6 may be employed 110 as an abutment which may be engaged by the thumb of the hand of the operator,

while the forefinger is engaged with the free portion of the ring diametrically opposite the tongue, thus allowing the ring to be moved upwardly to a vertical position 5 preliminary to the cap displacing action in a ready and convenient manner.

It will be observed that by the use of an opener of the character described, the necessity of employing a separate opener will 10 be avoided, and a more convenient type of opener provided; one which is simple and cheap of construction and may be employed without materially adding to the cost of the cap, and one which will enable the cap 15 to be removed in a ready and convenient manner.

Having thus described my invention, I claim:

1. A bottle cap having a ring-shaped cap-
20 removing member attached to the periphery

thereof, normally encircling the cap and adapted to be turned from such position to a position in a plane tangential to the periphery of the cap.

2. In a cap remover, a flanged cap having 25 its flange provided at one side with a depending integral tongue, and a lever comprising a ring of slightly greater diameter than the cap and normally disposed horizontally below the cap, said ring being connected at one side with said projection and extending at its opposite side outwardly beyond the adjacent side of the cap, adapting it to be swung upwardly from the cap to 30 a vertical position in alignment with said tongue or projection and in a plane tangential to the periphery of the cap.

In testimony whereof I affix my signature.

AUGUST E. STEINHAUSER.
